Primary Examiner — S. Bryan Reinholdt, Jr.(74) Attorney, Agent, or Firm — H. Brock Kolls(57) CLAIM

The ornamental design for tongs, as shown and described.

DESCRIPTION

FIG. 1 is a perspective view of the tongs according to my new design; and

FIG. 2. is a side elevation view thereof,

FIG. 3 is a front perspective view of the lower of the two parts of the tongs of FIG. 1;

FIG. 4 is a back perspective view thereof;

FIG. 5 is a top plan view thereof; and,

FIG. 6 is a bottom plan view thereof.

The dashed lines and the areas within them shown in FIGS. 1, 2, and 4 depict portions of the tongs that form no part of the claimed design.
